DESIGN FOR A COMBINED SANDGLASS TIMER AND CASE

Jacob M. Weiss, Brooklyn, N. Y.

Application April 2, 1938, Serial No. 76,251

Term of patent 7 years

To all whom it may concern:

Be it known that I, Jacob M. Weiss, a citizen of the United States, residing at 1558-54th Street, in the Borough of Brooklyn, county of Kings, city and State of New York, have invented a new, original, and ornamental Design for a Combined Sandglass Timer and Case, of which the following is a specification, reference being had to the accompanying drawing; forming part thereof.

Fig. 1 is a perspective view of a combined sandglass timer and case showing my new design; and

Fig. 2 is a perspective view thereof in open position.

The characteristic features of my design reside in the sandglass timer disclosed, arranged within a case and secured thereto with a clip, substantially as shown.

I claim:

The ornamental design for a combined sandglass timer and case, substantially as shown and described.

JACOB M. WEISS.
